RECEPTACLE FOR PACKAGING LIQUID CONTAINERS

Anthony L. Nugey, 1271 Pierpont St., Rahway, N.J.

Filed Apr. 26, 1960, Ser. No. 24,851

2 Claims. (Cl. 229—52)

I have invented an improvement in receptacles for packaging liquids in cans, bottles and other containers; and particularly a portable receptacle of such design that it can be easily carried away by a customer from the place where beverages, such as beer, soft drinks, milk, etc., are kept for sale.

An important object of this invention is to provide a carrier of such construction that it can be easily kept in stock in collapsed or folded condition and quickly set up in the form desired for its intended use.

Another object is to provide a portable carrier for holding cans of beer, for example, made out of water-proof sheet material, in the form of a blank; having well defined parts that can be readily manipulated to set up the receptacle when it is to be filled with containers of liquids, then neatly and completely sealed, and opened at any time thereafter without implements or mechanical appliances of any kind; when the contents are to be taken out.

In its preferred form, the receptacle is produced by bending a blank of sheet material having portions or sections for the bottom, sides, ends and top; hinge-connected to one another along score lines so that the various sections can be bent into final position.

My improved receptacle is a fully enclosed carrier for packaging cans or bottles, and is made from a single sheet of flexible corrugated fiber or cardboard, to permit quick and easy filling and removal of contents.

Another object of this invention is to provide a fully enclosed carrier for containers of liquids adapted to prevent the exposure of cans or bottles therein to the atmosphere.

A further object is to provide a fully enclosed carrier for containers of liquids requiring a minimum of material for manufacture and utilization.

A still further object of the invention is to provide a fully enclosed carrier for containers of liquids comprising parts which enable it to be shipped in folded condition and afterwards bent into place by the packer of bottles or cans in his place of business.

An additional object is to provide a carrier for containers of liquids made of foldable sheet material having locking means for preventing unauthorized removal of the cans or bottles therein after the carrier has been filled and sealed.

Still another object is to provide a carrier of containers of liquids that is damp proof and moisture proof throughout.

Yet another object of this invention is to provide a fully enclosed carrier of containers of liquid which will keep out heat effectively by greatly reducing heat transfer due to radiation, and by air leakage, so that goods cooled by refrigeration, will keep cold up to eight hours.

Other objects and advantages and the nature of the invention are clearly set forth in the ensuing description and the novel features are pointed out in the claims. The drawings illustrate an embodiment of the invention, but I reserve the right to make changes in structural details which are within the scope of the invention and covered by the meanings of the general terms in which the claims are expressed.

On said drawings:

FIGURE 1 is a plan view of a blank of cardboard or other sheet material comprising parts which can be bent

2

to set up the receptacle or carrier in practical form for use.

FIGURE 2 is a top plan of a piece of sealing tape for locking the parts of the carrier in closed position.

FIGURE 3 is a vertical longitudinal section through the completed carrier.

FIGURE 4 is a perspective view of the carrier as it will appear when completed and filled.

FIGURE 5 is a cross section of the completed carrier.

FIGURE 6 is a plan view of another form of sealing tape.

FIGURE 7 is a perspective view similar to FIGURE 4 with the tape of FIGURE 6 attached; and

FIGURE 8 is a perspective view of the carrier with the various parts in partly set-up positions.

A blank as shown in FIGURE 1 is indicated as a whole by the numeral 1 and the middle portion or section 2 thereof is to serve as the bottom of the carrier when finished. To this portion are attached the parts 3 to serve as the sides, which are hinge-connected to the bottom 2 along score lines 4. The side portions are of course as long as the bottom; and to the bottom between the sides are attached the portions or sections 5 to serve for the ends, these portions being hinge-connected to the terminal edges of the bottom 2 along transverse score lines 6. Beyond the sections 5 are the sections 7, hinge-connected to the sections 5 along transverse score lines 8. These two sections 7 together being as long as the bottom two and adapted to serve for the top to close the carrier in its completed set-up condition.

At the sides of each top section 7 are flaps 11 hinge-connected along longitudinal score lines 12 which are extensions of the score lines 4; and at the outer extremities of the sections 7 are the handles 9 having openings 10 for the fingers. These sections 9 are also hinge-connected to the sections 7.

The opposite ends of the side sections 3 have terminal extensions or flaps 13 hinge-connected to the sides along score lines which are extensions of the score lines 6. These extensions or flaps 13 are cut free along all the edges, except at the score line 6, and they have shouldered edges 14 adjacent the top edges 15 of the side sections 3.

To manipulate the blank so as to set up the carrier, the various parts are turned up as shown in FIGURE 8. The side portions 3 are folded around the score lines 4, and the end portions 5 are turned up around the score lines 6. The flaps 13 are bent so that they lie along the inner faces of the ends 5 and the flaps 11 are turned down so they pass within the container and lie against the inner faces of the sides 3. The cans or bottles can be easily stored between the sides 3 and flaps 11 before the top sections 7 are forced down into complete closing position, and then, because of the shouldered edges 14 of the flaps 13, the top sections are flush with and between the upper edges 15 of the sides 3. Also, as fully shown in FIGURE 1, the flaps 11 terminate just short of the end portions 5, and can be folded into the box above the portion 2. Hence the end portions 5 can be folded snugly against the flaps 5.

The handles 9 are of course turned up as indicated in FIGURE 4 and the sealing strip 16 of FIGURE 4, which has adhesive on one face, is attached by slipping the handle 9 through the slot 17, pasting the strip to the meeting ends of the portions 7, and the ends 19 are made to stick against the sides 2. When the carrier is to be opened the cords 18, which extend across the tape 16 under it at the sides and have protruding loops at their ends, can easily be pulled to tear the strip 16 so that the tops 7 can be raised by pulling up on the handles 9; for the box as shown in FIGURE 4. When the carrier is built as shown in FIGURE 7, without handles, the

strip 16a shown in FIGURE 6 is pasted across the top of the carrier along the adjacent edges of the sections 7, and this type of strip can be ripped across by pulling on the cord 20, which extends centrally along the tape as far as the ends 19, and then across the tape; so that when the loop at the middle of this cord is pulled, the tape is severed along the middle and at the sides of the container, and the top sections 7 are liberated.

I have discovered that light, heat and air cause early deterioration of unprotected flexible corrugated, fiber or cardboard. Similarly dampness permits passage of heat more rapidly than when such material is dry. Dampness also supports formation and growth of microorganisms and molds.

I have overcome these disadvantages by encasing both inside and outside surfaces of the carrier with aluminum foil, aluminum pigment, or any other suitable material. These substances, particularly aluminum foil and aluminum pigment have a high reflectivity for radiant heat and assure permanent waterproofing of the flexible corrugated, fiber or cardboard from which the carrier is made.

The aluminum foil is affixed to all surfaces of the carrier by means of waterproof adhesive. The aluminum pigment is sprayed, rolled or painted thereon. Aluminum foil or aluminum pigment are applied to the flexible corrugated, fiber or cardboard sheets prior to forming and cutting of the carriers shown in FIG. 1, and indicated in part at 20 in FIGS. 1, 4, 7 and 8.

I may use aluminum foil on all exterior surfaces and 30 aluminum pigment on interior surfaces, or vice versa; or use aluminum foil on both surfaces; or aluminum pigment on both surfaces.

Having described my invention, what I believe to be new is:

1. A carrier receptacle for containers of liquids therein comprising bottom, side, end and top portions, the side portions having terminal flaps overlying the inner faces of the end portions, the top portions being connected to the end portions and having flaps at the sides thereof to 40 lie against the inner faces of the side portions, said top portions having matching upturned handles at their edges extending across the middle of the container, the flaps

on the side portions having shouldered upper edges below the upper edges of the sides so that the top portions in closed position are flush with the upper edges of the side portion and lie between said edges and an adhesive strip secured over the adjacent edges of the top portions and the upper edges of the sides, and having a rip cord across its lower face along said side portions, said strip having a central slot through which the handles project, the outer faces of all said portions being covered with a waterproof layer comprising aluminum, the flaps on the side portions terminating short of the bottom of the receptacle.

2. A carrier receptacle for containers of liquids therein, comprising bottom, side, end and top portions, the side portions having terminal flaps overlying the inner faces of the end portions, the top portions being connected to the end portions and having flaps at the sides thereof to lie against the inner faces of the side portions, the flaps on the side portions having shouldered edges below the upper edges of the side portions, so that the top portions in closed position are flush with the upper edges of the side portions, an adhesive strip secured over the adjacent edges of the top portions and the upper edges of the side portions, and rip cord means on the lower face of said strip to tear said strip when the receptacle is to be opened, the outer faces of all said portions being covered with a waterproof layer comprising aluminum, the flaps on the side portions terminating also short of the bottom portion of said receptacle.
